[57] CLAIM

The ornamental design for a corner support for luggage, as shown and described.

DESCRIPTION

FIG. 1 is a perspective view of a corner support for luggage, showing my new design, with a portion of an automobile trunk and articles positioned therein in broken lines for illustrative purposes only and forming no part of the claimed design;

FIG. 2 is a side elevational view thereof;

FIG. 3 is an opposite side elevational view thereof;

FIG. 4 is a front elevational view thereof;

FIG. 5 is a rear elevational view thereof;

FIG. 6 is a top plan view thereof; and,

FIG. 7 is a bottom plan view thereof.
